BANDAGE

Owen E. Flynn, Los Angeles, Calif.

Application July 22, 1938, Serial No. 220,709

6 Claims. (Cl. 128—335)

This invention relates to improvements in bandages.

The general object of the invention is to provide a novel readily applied bandage.

5 A more specific object of the invention is to provide a novel surgical bandage which is particularly adapted to close and support a wound and which will in many cases eliminate suturing and consequent suture scars.

10 Another object of the invention is to provide a novel surgical bandage which permits the wound to drain.

Another object of the invention is to provide an improved surgical bandage which need not be removed for observation of the wound.

15 Another object of the invention is to provide a novel improved surgical bandage wherein the wound may be exposed to sunlight or other forms of treatment without removal of the bandage.

20 Other objects and advantages of my invention will be apparent from the following description taken in connection with the accompanying drawing, wherein:

Fig. 1 is a perspective view of the improved 25 surgical bandage embodying the features of my invention;

Fig. 2 is an enlarged perspective view showing the construction of the eyelets;

Fig. 2A is an enlarged perspective view showing 30 a modified form of eyelet;

Fig. 3 is a cross section on an enlarged scale of one of the connecting threads;

Fig. 4 is a perspective view showing the improved 35 bandage shown in Fig. 1 being applied to a wound;

Fig. 5 is a sectional view showing the improved bandage being applied to a wound;

Fig. 6 is a sectional view showing the improved bandage after application;

40 Fig. 7 is a perspective view showing an adhesive shim which may be used with the improved bandage; and

Fig. 8 is a sectional view of the improved 45 bandage as used with the adhesive shim shown in Fig. 7.

Referring to the drawing by reference characters, I have indicated my improved bandage generally at 10. As shown in Fig. 1 the bandage 50 includes a pair of rectangular tabs 11 and 12 connected by a series of parallel threads 13 strung through a series of eyelets 14 on another rectangular tab 15.

The tabs 11, 12 and 15 are preferably made 55 of suitable fabric material coated on one side

with some adhesive substance such as zinc oxide. For convenience each of the adhesive surfaces is covered with a strip 16 of gauze or similar material which is readily removable prior to use.

The threads 13 as shown in Fig. 3 are preferably 5 impregnated and coated with some material such as synthetic cellulose, rosin, or wax 17 containing suitable antiseptic agents such as are in common use and are fastened to the tabs 11 and 12 by the adhesive surfaces described above.

10 As shown in Fig. 2 the eyelets 14 are formed by alternate stitches of continuous thread 18 stitched through the tab 15 and through a reinforcing strip 19 laid thereon, the tab 15 being folded back upon itself as at 20.

15 In Fig. 2A, I show a modified form of eyelet 14' mounted on the tab 15' wherein each eyelet is a separate piece of formed wire the ends 21 of which pierce the tab 15' and a reinforcing strip 19' and are then bent over as clearly 20 indicated.

In use the protective strips 16 are first removed from the tabs 11, 12 and 15 exposing the adhesive surfaces thereon. As shown in Figs. 4, 5 and 6 the tab 15 is applied to one side of the wound 25 22 and the tab 12 to the other. The tab 11 is then applied to the upper surface of the tab 12 after the threads 13 have been drawn sufficiently taut, thus closing the wound 22 but leaving it exposed for treatment, observation and 30 drainage.

In Fig. 7, I have shown an adhesive shim 23 having a central core 24 of material, such as lead, which is flexible but not resilient. Surrounding the core 24 is packing material 24', 35 such as cotton, which is encased in adhesive surfaced material 25 part of which is covered with a strip 26 of plain material leaving only a portion of the adhesive surface exposed.

40 In use these shims are arranged parallel to and adjacent the wound 22 with the portions 26 upwardly as shown in Fig. 8. The tabs 11, 12 and 15 are then applied as described above, the threads 13 now being raised conveniently above the wound 22, and a downward pressure applied surrounding the wound 22 which tends to prevent the edges of the wound from curling inwardly. The portion 26 being free from glue allows the threads to slide unimpeded.

45 It will be apparent that small differences of construction and form may be made without departing from the spirit of the invention. For instance, the connecting threads may be woven into the tab material forming an integral part 55

thereof instead of being applied to the adhesive surface as described.

The bandages may be made in various sizes and shapes adapted to particular purposes and 5 may be prepared in individual form or cut from strips or rolls as needed.

From the foregoing description it will be apparent that I have invented a novel improved surgical bandage which has many advantages 10 over previous structures.

Having thus described my invention I claim:

1. In a surgical bandage, a pair of substantially rectangular adhesive tabs spaced apart and connected by a plurality of parallel antiseptic-impregnated threads, a third adhesive tab adapted 15 to be applied adjacent to a wound, said tab having eyelets adjacent one edge thereof, said eyelets comprising alternate stitches of a continuous antiseptic-impregnated thread, and each 20 of said eyelets engaging one of said plurality of threads, each of said tabs having a protective cover removable before use and being adapted to be applied adjacent a wound and to hold said wound closed but exposed.

2. In a surgical bandage, a pair of substantially rectangular adhesive tabs spaced apart and connected by a plurality of spaced parallel antiseptic-impregnated threads, a third adhesive tab having a reenforcement and having eyelets adjacent one edge thereof, said eyelets comprising 25 alternate stitches of a continuous antiseptic-impregnated thread passing through said reenforcement and said thread tab, said eyelets respectively engaging respective ones of said 30 threads, said tabs each having a removable protective cover, said tabs being adapted to be applied adjacent a wound and to hold said wound closed but exposed.

3. In a bandage, a tab having adhesive on one face and adapted to be applied adjacent to a wound, said tab having a plurality of spaced eyelets projecting therefrom, said eyelets comprising alternate stitches of a continuous antiseptic-impregnated thread and a pair of tabs 5 having adhesive thereon, said last mentioned tabs being spaced apart and connected by a plurality of parallel antiseptic-impregnated threads, the respective ones of said plurality of threads 10 passing through the respective ones of said eyelets, each of said tabs having a removable cover for the adhesive surface thereon.

4. In a surgical bandage, an adhesive tab having projecting eyelets adjacent one edge, said 15 eyelets being formed of wire and each having bent ends piercing and engaging said tab and a reenforcing strip thereon, a pair of tabs, and threads connecting said pair of tabs, said threads being interlaced with said eyelets. 20

5. In a surgical bandage, a pair of members provided with adhesive and adapted to be applied about a wound, a third adhesive member adapted to be superimposed on one of the said 25 pair of members, threads connecting the said pair of members and said third member and spaced loops on the third member slidably engaging the threads.

6. In a surgical bandage, a pair of adhesive tabs spaced apart and connected by parallel 30 threads, a third adhesive tab having eyelet members thereon, said eyelet members comprising loops with the ends of the loops on said third tab, the respective eyelet members slidably receiving respective ones of said threads, said tabs 35 being adapted to be applied adjacent a wound and to hold said wound closed.

OWEN E. FLYNN.
